(No Model.)

H. LAMPERT, Jr.
SECONDARY BATTERY.

No. 437,848.

Patented Oct. 7, 1890.

UNITED STATES PATENT OFFICE.

HENRY LAMPERT, JR., OF CHICAGO, ILLINOIS.

SECONDARY BATTERY.

SPECIFICATION forming part of Letters Patent No. 437,848, dated October 7, 1890.

Application filed January 31, 1889. Serial No. 298,191. (No model.)

To all whom it may concern:

Be it known that I, HENRY LAMPERT, Jr., of Chicago, in the county of Cook and State of Illinois, have invented a certain new and useful Secondary Battery; and I do hereby declare that the following is a full, clear, and exact description thereof, reference being had to the accompanying drawings, and to the letters of reference marked thereon, which form a part of this specification.

This invention relates to an improvement in secondary batteries; and it consists in the matters hereinafter described, and pointed out in the appended claims.

In the accompanying drawings, illustrating the manner in which my improved method may be carried out, Figure 1 is a plan or face view of one of the plates of a storage-battery adapted for connection in the novel manner proposed by me. Fig. 2 is a side view of said plate. Fig. 3 is a vertical section of a portion of my improved battery upon line 3 3 of Fig. 1, showing the manner of securing the plates together. Figs. 4 to 9 are fragmentary sectional views showing other forms in which the plates may be made.

As shown in said drawings, A A are a series of plates of a storage-battery, each of said plates being provided with a lateral projection or hub A'. The hubs A' are provided with apertures or openings extending through the hubs and plates, said openings being constructed to receive the ends of the hubs upon the adjacent plates and forming a tubular passage when the plates are put together. As shown in the drawings, the hubs A' are provided with rabbets a to receive the ends of the hubs of adjacent plates, and with inwardly-tapered recesses a', extending from the rabbets to the outer ends of the hubs, so that when the plates are put together a series of projections a² a² are formed within the tubular opening formed by the recesses of the several hubs. The several plates when placed together in the position shown in the drawings, Fig. 3, are connected by pouring molten metal into the tubular recess or opening formed by the apertures of the several hubs, the solidified metal by its engagement with the inwardly-projecting parts of the hubs holding the plates securely together, and thereby forming a strong and permanent connection between the same.

The plate A², which forms the end plate of the series, is provided with a hub A³, having 55 a recess a³, which does not extend through the plate, so that when the several plates are placed together the closed recess a³ will form a tight bottom to the tubular passage, thereby preventing the escape of molten metal when 60 poured into the upper part of said passage. The use of the plate A² thus formed has the advantage of rendering unnecessary any special device for closing the aperture in the lower plate at the time of pouring the metal; 65 but as far as the main features of my invention are concerned the employment of a plate thus formed is not strictly necessary.

B indicates a tubular extension or thimble shaped like the hubs A' A', and provided 70 with a rabbet b and a tapered recess b', said rabbet being arranged to engage the hub A' on the adjacent plate A. The said thimble B serves to form a shank, by which the electric conductor may be connected with the 75 plates.

C indicates the metal rod or core of fusible metal, by which the several plates are connected in the manner above described. Said rod or core is not intended to be necessarily 80 of sufficient strength or rigidity to support the several connected plates, but is intended mainly as a tie to hold the hubs of the several plates in contact by its engagement with said hubs, thereby acting, together with said 85 hubs, to rigidly connect the plates.

D, Fig. 3, indicates a metal rod, preferably of copper, which may be inserted in the tubular opening before the metal C is poured therein, and to which the conductor-wire 90 leading to the battery-plates is attached. Said rod D, when present, not only enables an electric conductor to be easily connected with the plates, but by extending through or past the several plates affords better 95 electrical connection with the plates.

In Fig. 4 is shown a somewhat different construction in the plates adapted for connection in the manner above described. In this case E E indicate plates, which are provided 100 with hubs E', having internal recesses e of cylindric form, and rabbets e' to receive the hubs E' of the adjacent plates, and internal ribs e², which by positive engagement with the metal core F, formed by pouring molten 105 metal into the tubular passage formed by the

several apertures, in the manner described, positively hold the plates from relative movement or separation.

Fig. 5 shows still another form in which the plates may be made, wherein the apertures of the plates are smooth and conical. In this instance G G are the plates provided with hubs G', which are conical upon their outer surfaces and within which are formed conical apertures g. The extreme end of each hub is adapted to fit within the conical aperture of the adjacent plate, so that the several plates may be engaged with each other, in the manner illustrated, to form tight joints between the parts in pouring the molten metal. The conical inner surfaces of the hubs, together with the end surfaces thereof, engage the metal core H, formed by pouring molten metal into the tubular passage formed by the several apertures in such manner as to prevent any shifting or endwise movement of the plates with reference to the core, so that the latter holds the same firmly together in the manner clearly illustrated in the drawings.

In Fig. 6 is shown a series of plates I I I, having conical hubs I' I', having apertures formed through them in the same manner as before described. Said apertures, however, have conical parts i, adapted to receive the upper ends of the hubs of adjacent plates, and oppositely-inclined conical parts i', making the apertures smaller in diameter at the middle parts than elsewhere. This construction also gives a positive engagement of the plates with the fusible metal core J with the same advantages above pointed out. It is not, however, essential that the apertures of all or any of the plates should contain internal projections adapted to engage the fusible metal core, inasmuch as the plates may be held from separation or movement upon the core by positive engagement of the end plates of the series with the core, or when the plates are of fusible metal and the metal to form the core is poured into the tubular passage through the plates when heated to a temperature higher than that of the fusing-point of the plates a fused joint will be formed between the plates and the core, and said parts will be permanently and strongly united. This method of uniting the plates, in the case of plates used for storage-batteries, is preferred, for the reason that it forms continuous electrical connection or union between the plates and the core calculated to perfectly transmit the electric current in the operation of the battery.

In Fig. 7 is shown a construction wherein plates K K K are provided with hubs K', having cylindric recesses or openings k and rabbets k' to receive the hubs of adjacent plates. L is a core of fusible metal filling the cylindric passage formed by the several recesses k when the parts are placed together and united to the several plates by fusing, so

that the metal of the plates and core is practically continuous after the parts are united.

Fig. 8 illustrates a series of plates M M M, having hubs m m, provided with cylindric apertures m' and without any rabbets or interfitting surfaces on the two parts, the ends of the hubs on the several plates being merely placed against the adjacent plates and held in this position by a clamping device or otherwise during the time the metal is being poured into the tubular passage formed by the several apertures m'. In this instance, also, the fusible core N is formed by pouring the metal at a temperature higher than the fusing-point of the metal composing the plates, so that fused joints are formed in the same manner as before described.

In Fig. 9 I have shown a construction wherein a series of plates are united by positive engagement of the end plates of the series with the fusible metal core. In this instance O O are intermediate plates of the series, and P Q are end plates of the series. The plates O O have hubs O', provided with cylindric apertures o. The bottom plate P is provided with a hub p, having a closed recess p', larger at its bottom than at its top. The upper plate Q has a hub Q', provided in its lower part with an opening q of the same size as the opening o, and in its upper part with a larger recess q'. The plug R of fusible metal, in a construction of this kind, has enlarged heads r r' at its opposite ends, by which the parts are positively held together.

I claim as my invention—

1. The herein-described storage-battery, consisting of apertured plates arranged side by side with the apertures in alignment, and a filling of fusible metal within said apertures rigidly securing the plates together.

2. The herein-described storage-battery, consisting of plates arranged side by side and provided with apertured hubs registering with each other, and a filling of fusible metal within the apertures of the hubs.

3. The herein-described storage-battery, consisting of plates arranged side by side and provided with hubs registering with each other, each of said hubs having a tapered recess, and a rabbet at one side to receive the hub of the adjacent plate, the continuous passage formed by the recesses in the hubs being filled with fusible metal.

4. The herein-described storage-battery, consisting of plates of fusible metal cast with hubs upon their surfaces and arranged side by side, and a filling of fusible metal within the passage formed by the openings in the hubs.

In testimony that I claim the foregoing as my invention I affix my signature in presence of two witnesses.

HENRY LAMPERT, JR.
